DESIGN FOR AN ATOMIZER

Armand Blatt, New York, N. Y.

Application February 25, 1948, Serial No. 144,721

Term of patent 7 years

(Cl. D83—1)

To all whom it may concern:

Be it known that I, Armand Blatt, a citizen of the United States of America, residing in New York city, county of New York, and State of New York, have invented a new, original, and ornamental Design for an Atomizer, of which the following is a specification, reference being had to the accompanying drawing, forming part thereof, wherein,

Figure 1 is a perspective view of an atomizer, showing my new design.

Figure 2 is a view similar to Figure 1, showing the top and body portions of the atomizer in separated positions, and

Figure 3 is a top plan view of the atomizer.

I claim:
The ornamental design for an atomizer, substantially as shown.

ARMAND BLATT.
